UNITED STATES PATENT OFFICE

166,056

ENVELOPE MOISTENER

John C. Vollmert, Pampa, Tex.

Application September 5, 1951, Serial No. 16,513

Term of patent 14 years

(Cl. D74—10)

To all whom it may concern:

Be it known that I, John C. Vollmert, a citizen of the United States of America, residing at Pampa, in the county of Gray and State of Texas, have invented a new, original, and ornamental Design for an Envelope Moistener, of which the following is a specification, reference being had to the accompanying drawing, forming part thereof.

Fig. 1 is a perspective view of an envelope moistener, showing my new design.

Fig. 2 is an end view of the envelope moistener shown in Fig. 1, and.

Fig. 3 is a bottom plan view of the envelope moistener.

I claim:

The ornamental design for an envelope moistener, as shown.

JOHN C. VOLLMERT.
